WIRING BOARD HANDLE

David L. Barnett, Phoenix, Ariz., assignor to General Electric Company, a corporation of New York

Filed Dec. 28, 1962, Ser. No. 72,983

Term of patent 7 years

(Cl. D10—8)

FIG. 1 is a perspective view of a wiring board handle embodying my new design.

FIG. 2 is a top plan view thereof.

FIG. 3 is a front elevational view thereof.

FIG. 4 is a bottom view thereof.

FIG. 5 is a side elevational view thereof.

The rear of the wiring board handle is substantially flat and plain.

I claim:

The ornamental design for a wiring board handle, as shown and described.
